United States Patent Office

Des. 187,781

Patented May 3, 1960

187,785

TRAILER

Paul H. Zimmer, Alexandria, Ind., assignor to Zimmer Industries, Inc., Elwood, Ind., a corporation

Application September 23, 1958, Serial No. 52,735

Term of patent 14 years

(Cl. D14—3)

FIG. 4

Fig. 1 is a front elevation view of the door unit of the trailer, shown in Fig. 4;

Fig. 2 is a sectional view taken on line 2—2 of Fig. 1;

Fig. 3 is a vertical sectional view taken on line 3—3 of Fig. 1; and

Fig. 4 is a perspective view on a reduced scale of a trailer showing my new design.

The dominant features of my design reside in the portions shown in full lines.

I claim:

The ornamental design for a trailer, as shown and described.
